UNITED STATES PATENT OFFICE.

EMORY A. ISABELLE, OF CHICOOPEE, AND HARRY J. NEWELL, OF SPRINGFIELD, MASSACHUSETTS.

BASEBALL GAME.

Application filed August 14, 1925. Serial No. 50,228.

This invention relates to games and more particularly to a baseball game which may be played by two or more persons representing two teams of opposing dummy players, wherein the game may be played in accordance with the established rules of organized baseball.

The principal object of this invention is to provide a baseball game in which each person endeavors to roll a ball against a relatively narrow and rotatably mounted indicator which after rotation will occupy a position of rest and point to one of a plurality of associated "playing" indicia whereby a "hit" or "out" or "play" of the offensive player or players will be decided by the rules of the game which correspond to the "playing" indicia.

Another object of the invention lies in the provision of a plurality of pockets for receiving the discharged ball should the latter fail to hit the indicator and "playing" indicia associated with the respective pockets to indicate "balls" and "strikes".

These and other objects will more fully appear and the nature of the invention will be more clearly understood by following the description, the appended claims, and the several views illustrated in the accompanying drawings, in which—

Fig. 1 is a plan view of a game board constructed in accordance with our invention,

Fig. 2 is a longitudinal sectional view thereof,

Fig. 3 is a detailed sectional view showing the manner employed for mounting the dummy batter on the game board, and

Fig. 4 is a detailed sectional view, taken on line 4—4 of Fig. 1, showing a ball seated in one of the pockets.

Referring to the drawings, wherein similar characters designate corresponding parts throughout the several views,

The invention aims to provide a game board 5 having a baseball diamond 6 located thereon. Associated with the baseball diamond 6 is a stationary revoluble batter 7. This batter 7 is in the form of a player holding a downwardly extending bat or indicator 8. This batter is mounted to rotate about a vertical axis concentric with a surrounding dial 9 and "playing" indicia 10 printed or otherwise formed about its peripheral, the radius of the dial being such as to position the lower end of the bat or

indicator 8 in close proximity to said "playing" indicia 10. This "playing" indicia 10 preferably consists of a series of numbers running from 1 to 13, which are arranged in irregular order. The baseball diamond 6 includes the usual home plate 11, first base 12, second base 13, third base 14, and pitcher's box 15. The batter 7 is located adjacent the home plate 11, whereby the bat or indicator 8 thereof in its normal position extends to a point directly above the center of the home plate 11, and in a plane at right angles to a line extending from the home plate 11 to pitcher's box 15.

Associated with the game board are two teams A and B respectively, consisting of movable dummy players or game pieces 16 and 17 respectively, the game pieces of the respective teams being preferably colored differently. There are 9 of these dummy players or game pieces on each of said teams.

Located on the game board 5 directly in rear of the home plate 11 is a plurality of pockets 18 and 19, there being 10 of the pockets 18 and 9 of the pockets 19 shown on the drawings. It is understood, however, that the number of these pockets may be varied as may be desired. Associated with each pocket 18 is "playing" indicia 20 which in this instance consists of the letter "B". Associated with each pocket 19, is "playing" indicia 21 which in this instance consists of the letter "S". The letter "B" indicates a "ball" whereas the letter "S" indicates a "strike".

A ball, marble, or other spherical projectile 22 is also associated with the game board and is adapted to be rolled by the persons playing the game. This ball is normally positioned in the pitcher's box 15 in rear of a line 23 formed therein. This ball or projectile 22 is rolled toward the batter 7 and the object is to cause said ball to hit the bat or indicator 8, and thereby revolve the batter 7, whereby the bat or indicator 8 will finally occupy a position of rest and point to one of the numbers forming the "playing" indicia 10, associated with the dial 9. The numbers 1 to 13 of the "playing" indicia corresponds to the rules of the game which are outlined as follows:

1. One-base hit.
2. Two-base hit.
3. Three-base hit.
4. Home run.

5. Double play. Batter is out if no runners are on bases.

6. Fly out. If one man is out runner scores from third base. Men on first or second do not advance.

7. Out at first. Runners hold bases. Filder's choice.

8. On base by error. All runners advance. Runner on third scores.

10. Fouled out. Runners do not advance.

10. Foul strike. This number three times puts batter out. If there are two strikes on batter this number puts batter out. Catcher caught third strike.

15. 11. Runner steals base or home base, batter gets credit for a ball.

12. Safe bunt. Runners advance. Runner on third out trying to score.

13. Sacrifice hit. All runners advance.

20. If no runner on base batter is out. Squeeze play runner scores from third unless it is the third out.

25. It will, of course, be understood that the above rules may be changed if desired as the above are merely illustrative.

30. It will be noted that the lower end of the batter indicator 8 is positioned directly above the game board 5 at a distance considerably less than the diameter of the projectile 22 and consequently the projectile will not pass directly under the indicator but will engage the same and cause the batter 7 to be rotated.

35. We preferably provide the game board

with marginal side and end walls 24 and 25 respectively. To this end we preferably mount the game board 5 within a position which includes the bottom 26, the side and end walls 24 and 25, and a removable clo-

40. sure 27, which we have indicated by dotted lines in Fig. 2. The game board 5 is of a size to snugly fit within the side and end walls. The game board 5 is preferably supported above the bottom 26 through the

45. medium of spacing blocks 28. The batter 7 is revolvably mounted to swing about the vertical axis through the medium of a pivoted pin 29, which extends through the bottom 26, a filler block 30, the game board 5, and through the batter 7.

50. The game is usually played by two persons each person rolling the surface projectile 22 against the batter indicator 8, and moving the game pieces or dummy players around

55. the baseball diamond in accordance with the rules of the game until three outs are obtained. The other person then takes his turn and operates the game in a similar manner.

It will be noted that the projectile 22 is 60 rolled by the hands of each person from a point in advance of the line 23 in the pitcher's box 15, and should the projectile miss the bat or indicator 8 and become deposited in one of the pockets 18 or 19, the batter

will be credited with a ball or strike depending in which pocket the projectile becomes seated.

65. While we have herein shown and described the preferred form of our invention, we desire it to be understood that numerous variations and alterations in the general construction and arrangements of the parts thereof may be adopted from time to time as we may deem expedient and which will neither depart from the spirit of the invention nor the 70 scope of the claims.

75. Having thus described our invention, what we claim as new and desire to secure by Letters Patent, are:

1. In a baseball game, the combination 80 with a game board, of a baseball diamond upon said board including a home plate and a pitcher's box, the latter being disposed within the diamond, a plurality of offensive game pieces adapted to be movably positioned upon said diamond, a revolvable player mounted on said board adjacent the home plate to rotate about a vertical axis, said player being provided with a downwardly extending indicating arm adapted to have 85 its free end travel over said home plate, a dial located on the board and arranged concentrically relative to said player, said dial including "playing" indicia for cooperation with the indicator to determine the movements and status of the game pieces, and an independent surface projectile operated from the pitcher's box for striking the indicator to rotate the same about the dial.

90. 2. In a baseball game, the combination 100 with a game board, of a baseball diamond upon said board including a home plate and a pitcher's box, the latter being disposed within the diamond, a plurality of offensive game pieces adapted to be movably positioned upon said diamond, a revolvable player mounted on said board adjacent the home plate to rotate about a vertical axis, said player being provided with a downwardly

105. extending indicating arm adapted to have its free end travel over said home plate, a dial located on the board and arranged concentrically relative to said player, said dial including "playing" indicia for cooperation with the indicator to determine the movements and status of the game pieces, and an independent surface projectile operated from the pitcher's box for striking the indicator to rotate the same about the dial.

110. 3. In a baseball game, the combination 110 with a game board, of a baseball diamond upon said board including a home plate and a pitcher's box, the latter being disposed within the diamond, a plurality of offensive game pieces adapted to be movably positioned upon said diamond, a revolvable player mounted on said board adjacent the home plate to rotate about a vertical axis, said player being provided with a downwardly

115. extending indicating arm adapted to have its free end travel over said home plate, a dial located on the board and arranged concentrically relative to said player, said dial including "playing" indicia for cooperation with the indicator to determine the movements and status of the game pieces, and an independent surface projectile operated from the pitcher's box for striking the indicator to rotate the same about the dial.

120. 4. In a baseball game, the combination 120 with a game board, of a baseball diamond upon said board including a home plate and a pitcher's box, the latter being disposed within the diamond, a plurality of pockets in said game board located behind the home plate for receiving said ball and having "playing" indicia associated therewith.

125. In testimony whereof we hereunto affix our signatures.

EMORY A. ISABELLE.
HARRY J. NEWELL.
